CLAIM

The ornamental design for a stand for annular computer peripheral, as shown and described.

DESCRIPTION

FIG. 1 is an upper perspective view of a stand for annular computer peripheral showing my new design; FIG. 2 is a lower perspective view thereof;

FIG. 3 is a top plan view thereof;

FIG. 4 is a bottom plan view thereof;

FIG. 5 is a view in front elevation thereof with the views in rear elevation and side elevation being mirror images thereof;

FIG. 6 is a view in front elevation of the stand for annular computer peripheral in use retaining an annular computer peripheral;

FIG. 7 is a cross-sectional view of the stand for annular computer peripheral in use retaining an annular computer peripheral taken along the line 7-7 in FIG. 6; and,

FIG. 8 is a perspective view of the stand for annular computer peripheral in use retaining an annular computer peripheral.

The broken lines illustrate environmental subject matter that forms no part of the claimed design.
